RECEIVING APPARATUS FOR COMMUNICATION SYSTEMS

Andrew J. Sorensen, Edgewood, Pa., assignor to
The Union Switch & Signal Company, Swiss-
vale, Pa., a corporation of Pennsylvania

Application June 21, 1941, Serial No. 399,136

9 Claims. (Cl. 179—82)

My invention relates to receiving apparatus for communication systems, and more particularly to receiving apparatus for communication systems for railway trains.

In communication systems of the type here contemplated, a carrier current is used. For telephone communication a carrier is modulated by the voice frequencies and a preselected side band of such modulated current is transmitted, the carrier and the other side band being preferably suppressed. At the receiving station such carrier telephone current is demodulated and current of the voice frequencies is supplied to a telephone receiver or a loud speaker. In such systems a calling or signaling current is needed and is usually effected by producing a current equivalent to the carrier modulated by a preselected frequency within the voice frequency range or modulated by a preselected relatively narrow band of voice frequencies. At the receiving station, the receiving apparatus includes a filter tuned sharply to such preselected band or single frequency and which is connected to the output terminals of the demodulator for passing current of such preselected frequency to special calling and signaling apparatus with the result that the receiving station is provided with an indication when telephone communication is desired. In such communication systems for railway trains the calling or signaling current is in some systems continuously supplied to the transmitting circuit at the sending station except during telephone communication for indicating at the receiving station that the system is in working order. When in such systems for railway trains the receiving apparatus is located on a vehicle of the train, the signaling current is sometimes used in part for governing the movements of the train. It is apparent that in such communication system the signaling and indication portion of the receiving apparatus must be effectively influenced by the signaling current and must be non-responsive to energy of the preselected voice frequency occurring in the telephone current and must also be non-responsive to voltage surges created by extraneous magnetic fields.

Accordingly, a feature of my invention is the provision of receiving apparatus for communication systems incorporating novel and improved means responsive to a calling or signaling current.

Another feature of my invention is the provision of receiving apparatus for communication systems of the type here involved incorporating

novel means including an electromagnetic relay that is effectively energized by the signaling current energy appearing at the output terminals of the demodulator and additional amplifiers and sources of current are not required.

A further feature of my invention is the provision in receiving apparatus for communication systems of the type here contemplated of novel and improved signaling apparatus incorporating means that discriminates against voltage surges of short duration, but an application of voltage of greater duration, even though of lesser magnitude than the surge voltage, operates the signaling apparatus.

Again, a feature of my invention is the provision of receiving apparatus for communication systems incorporating novel and improved delay means for the signaling portion of the apparatus and wherewith a substantially uniform predetermined delay period is effected in the operation of the signaling means even when the signaling current frequency repeatedly occurs in the telephone current.

Again, a feature of my invention is the provision in receiving apparatus for communication systems for railway trains of calling and signaling means requiring relatively few parts and that is relatively low in cost.

Other features, objects and advantages of my invention will appear as the specification progresses.

The above features, objects and advantages of my invention I attain by providing an electromagnetic relay characterized by a relatively high sensitivity and which is connected to the output terminals of the demodulator through a rectifier and a filter tuned to pass current of a preselected frequency within the voice frequency range only, or at least to pass only a relatively narrow band of frequencies within the voice frequency range. The signaling current to be used in such a system is then made to have such preselected frequency or narrow band of frequencies and the relay is effectively energized and picked up in response to current of such preselected frequency or band of frequencies appearing at the output terminals of the demodulator and additional amplification and current sources are not required. A surge protector is preferably interposed in the connection of the rectifier to the filter to discriminate against voltage surges but to cause little attenuation to sustained flow of the signaling current.

Another relay is controlled over a front contact of the first mentioned relay, and the two

relays jointly control a first indication lamp which is illuminated to indicate the presence of the signaling or calling current, a second lamp which is illuminated to indicate the absence of signaling current, and a bell which is momentarily sounded when the signaling current ceases. The two relays also govern the connection of a loud speaker to the output terminals of the demodulator, the loud speaker being retained at an inactive condition when signaling current is received and being switched to an active condition when such current ceases.

A delay means in the form of a resistor and two condensers is associated with the two relays so that operation of the indication means is effected only after the signaling current is received for a predetermined time interval and such operation of the indication means is not effected due to energy of the preselected frequency occurring in the telephone current. A circuit arrangement is also included in the apparatus for quickly discharging a selected one of the condensers so that a charge cannot be built up on the condenser to cancel or shorten the predetermined delay period by repeated operations of the first mentioned relay because of repeated occurrences of the signaling frequency in the telephone current or because of repeated voltage surges.

The delay means associated with the control relays of my present application is similar to the delay means of my copending application for Letters Patent of the United States, Serial No. 372,902, filed January 2, 1941, for Receiving apparatus for train communication systems, and in which copending application such delay means is claimed broadly.

I shall describe one form of apparatus embodying my invention and shall then point out the novel features thereof in claims.

The accompanying drawing is a diagrammatic view showing a preferred form of apparatus embodying my invention when used for a communication system for a railway train. It will be understood, however, that my invention is not limited in its use to communication systems for railway trains and this one application will serve to illustrate the many places such apparatus is useful.

Referring to the drawing, the reference character IC designates an inductor mounted on a vehicle of a railway train in inductive relation to a transmitting circuit, not shown. Ordinarily, inductor IC is mounted on the train in inductive relation to the track rails since the track rails are preferably included in the transmitting circuit to which communication current is supplied at a station remote from the vehicle on which the apparatus of the drawing is mounted. Such transmitting circuit may be, for example, that covered by the Letters Patent of the United States No. 2,112,364, granted March 29, 1938, to L. O. Grondahl, for Electric train signaling system.

The electromotive forces induced in inductor IC in response to current flowing in the associated transmitting circuit are applied to the input side of an amplifier-demodulator AD. The amplifier-demodulator AD may be any one of several well-known types of such devices and is shown conventionally for the sake of simplicity since its specific structure forms no part of my present invention. It is sufficient for this application to point out that amplification and demodulation is effected by the device AD when a modulated carrier current is applied to its input

terminals and current of the modulating frequency appears at its output terminals. For example, it has been proposed for communication systems for railways to employ for telephone communication the upper side band of a carrier of 5700 cycles per second modulated by voice frequencies of the range of 500 to 2500 cycles per second. That is to say, the current transmitted over the transmitting circuit is a suppressed carrier upper side band telephone current of 6200 to 8200 cycles per second. For calling and signaling purposes, a current of the order of 6700 cycles per second is used, such current being the equivalent of the upper side band of the carrier of 5700 cycles modulated by the preselected voice frequency of 1000 cycles. Thus when electromotive forces of a frequency corresponding to that of the telephone current is induced in inductor IC current of the voice frequencies of 500 to 2500 is supplied to the output terminals of the demodulator, and when an electromotive force corresponding in frequency to that of the signaling current of 6700 cycles is induced in inductor IC a signaling current of 1000 cycles is supplied to the output terminals of the demodulator.

A filter F1 including a reactor 34, a condenser 13 and a transformer T1 is coupled to the output side of the amplifier-demodulator AD by primary winding 14 of transformer T1 being connected across the output terminals of the demodulator. The parts are so proportioned that filter F1 is tuned sharply to the preselected frequency of the signaling current, that is, it is tuned to pass only energy of 1000 cycles per second when signaling current of the frequency referred to hereinbefore is used. Thus, by transformer action, the signaling current is transferred from the output terminals of the amplifier-demodulator to secondary winding 15 of transformer T1 and telephone current of the voice frequencies of 500 to 2500 cycles per second is suppressed insofar as being supplied through filter F1 except when the voice frequency of 1000 cycles per second occurs in the telephone current.

An electromagnetic relay R1 is connected to secondary winding 15 of transformer T1 through a full wave rectifier 16. A surge protector or variable resistor TH, preferably of the type designated by the trade name "Thermistor" is interposed in the connection of rectifier 16 to secondary winding 15. Surge protector or variable resistor TH is characterized by thermal inertia and high initial resistance and substantially blocks or discriminates against voltage surges of short duration, but an application of such voltage of greater duration even though of lesser magnitude than the surge voltage is passed with little attenuation after a small delay.

Electromagnetic relay R1 is preferably of the polar type operated by direct current of one polarity only, and is characterized by a high sensitivity. For example, relay R1 may be of the type covered by a co-pending application for Letters Patent, Serial No. 365,039, filed November 9, 1940, by R. M. Laurenson, for Electrical relays. Relay R1 is connected to the output terminals of rectifier 16 to be energized by the current passed by filter F1, and it follows that relay R1 is effectively energized and picked up when a sustained flow of the signaling current is supplied to the amplifier-demodulator AD from the transmitting circuit through inductor IC; but that relay R1 remains deenergized and

released when telephone current is applied to the amplifier-demodulator from the transmitting circuit except when the voice frequency of 1000 cycles per second occurs in the telephone current. Furthermore, the surge protector TH is effective to suppress surges of current passed by filter F1 but causes little attenuation to the signaling energy after a short delay period. In other words, there is a short delay before energy can be applied to relay R1 due to the action of device TH, with the result that energy of the preselected voice frequency used for the signaling current when occurring in a telephone current is blocked from reaching relay R1, and also that voltage surges induced in inductor IC due to extraneous magnetic fields are blocked by device TH.

Relay R1 when picked up to close its front contact 17, completes an energizing circuit for another relay R2 which is preferably of the direct current type and which is effectively energized by current from a direct current source whose terminals are indicated at B and C.

Condensers C1 and C2, and a resistor 32 are associated with relay R2 to effect a delay period in the operation of that relay. Condenser C2 is permanently connected across the winding of relay R2. Condenser C1 is also connected across the winding of relay R2 over a connection including front contact 35 of relay R1 and back contact 21 of relay R2 as will be apparent from an inspection of the drawing. Thus, when relay R1 is picked up to close front contacts 17 and 35, a circuit is formed from terminal B over front contact 17 of relay R1, resistor 32, winding of relay R2 in multiple with both condensers C1 and C2 and thence to terminal C of the current source. Relay R2 is energized and picked up only after a delay period predetermined by the size of resistor 32 and by the capacity of the condensers C1 and C2, since it is necessary that condensers C1 and C2 be first charged before the relay R2 is effectively energized. The parts are so proportioned that condenser C1 is relatively large and provides a relatively long delay period in the picking up of relay R2. Condenser C1 is disconnected from the energizing circuit of relay R2 when that relay picks up to open its back contact 21, and hence when relay R1 is released to open the energizing circuit of relay R2, relay R2 is retained energized for a period predetermined by the capacity of condenser C2, since condenser C2 discharges through the winding of relay R2 to retain that relay energized. It is to be observed that when both relays R1 and R2 are released, condenser C1 is provided with a discharge circuit including back contact 21 of relay R2, a resistor 22 and back contact 23 of relay R1.

Relays R1 and R2 jointly control the connection of a loud speaker LS to the terminals of the amplifier-demodulator AD, and an indication means comprising two lamps L1 and L2 and a bell B1. With relay R2 picked up a circuit is formed from terminal B over front contact 27 of relay R2, lamp L1 and to terminal C, and lamp L1 is illuminated. Relay R2 when released completes a circuit including terminal B, back contact 28 of relay R2, lamp L2 and terminal C, and lamp L2 is illuminated. Subsequent to the release of relay R1 and before relay R2 is released at the end of its slow release period as effected by condenser C2, a circuit is formed from terminal B over front contact 27 of relay R2, back contact 29 of relay R1, bell B1 and to terminal C, and the bell B1 is sounded during this slow release

period of relay R2. When relay R2 is released, closing back contact 30, the operating winding of the loud speaker LS is connected across the output terminals of amplifier-demodulator AD over a circuit easily traced.

In describing the operation of the apparatus, I shall assume that at the start relays R1 and R2 are deenergized and the associated remote control station starts supplying signaling current to the transmitting circuit causing a sustained electromotive force of the frequency corresponding to the frequency of the signaling current to be induced in inductor IC. For example, such signaling current may be of 6700 cycles per second as referred to hereinbefore. The electromotive force is amplified and demodulated and signaling current of 1000 cycles per second is supplied from the output terminals of the amplifier-demodulator AD through filter F1, to rectifier 16, there being a brief delay in the application of the energy to the rectifier 16 due to the action of device TH. This signaling current is rectified and applied to relay R1, causing relay R1 to be effectively energized and picked up. Relay R1 on picking up to close front contacts 17 and 35 completes the energizing circuit for relay R2 and the connection of the condenser C1 to relay R2 and that relay is picked up after condensers C1 and C2 have been charged through resistor 32. As stated hereinbefore, condenser C1 is of relatively large capacity and hence provides a relatively long predetermined delay period in the picking up of relay R2. After relay R2 is picked up, condenser C2 is disconnected and relay R2 is then retained energized in multiple with condenser C2. Relay R2 on picking up to close front contact 27 causes lamp L1 to be illuminated as an indication that signaling current is being received. With the signaling current continuously transmitted, lamp L1 is continuously illuminated and forms an indication that the system is in working order. The loud speaker LS is now disconnected from the amplifier-demodulator and is in an inactive condition.

In the event the operator of the associated remote station desires to initiate telephone communication with the operator at the station of the receiving apparatus of the drawing, the operator at the remote station discontinues the sending of the signaling current with the result that relay R1 is at once deenergized and released. Relay R2 is retained picked up until condenser C2 is discharged and during the interval that relay R1 is released and relay R2 is picked up, the bell B1 is sounded as an audible indication that telephone communication can be expected. With relay R2 released at the end of its slow release period, the sounding of bell B1 is interrupted, lamp L1 is extinguished, lamp L2 is illuminated and loud speaker LS is connected to the output terminals of the amplifier-demodulator. The illumination of lamp L2 is an additional indication that telephone communication can be expected and in the event lamp L2 remains illuminated and no telephone current is shortly received, then lamp L2 serves to indicate an inoperative condition of the system, the operator at the receiving apparatus taking whatever steps are required by an inactive system.

Assuming telephone current is shortly transmitted from the associated remote station, the electromotive forces induced in inductor IC cause telephone current to appear at the output terminals of the demodulator, and the voice frequencies are reproduced at the loud speaker LS.

Such telephone current will not be passed by filter F1 except as the preselected frequency of 1000 cycles may occur in the telephone current. Such occurrence of energy of 1000 cycles in the telephone current would be ordinarily of short duration and would ordinarily be blocked by the device TH. In the event such energy persists for a period long enough to be passed by device TH, relay R1 is picked up but relay R2 is not picked up until after a relatively long delay period effected by condensers C1 and C2 and resistor 32 in the manner explained hereinbefore. Consequently energy of the signaling frequency occurring in the telephone current will not ordinarily at least, effect any change in the indication devices. Furthermore, if energy of the signaling frequency repeatedly occurs in the telephone current to cause relay R1 to be repeatedly picked up, it is to be noted that the condenser C1 is discharged each time that relay R1 is released due to the discharge circuit including back contacts 21 and 23 of the two relays, with the result that the predetermined delay period in the picking up of relay R2 is effected each time that relay R1 is picked up. In other words, repeated picking up of relay R1 does not cause a charge to be built up on condenser C1 that will eventually defeat the delay period effected in the picking up of the second relay R2.

When telephone communication is terminated then the associated remote station would again send the signaling current with the result that the apparatus is restored to its normal condition, that is, to the condition illustrated in the drawing.

From the foregoing description it is clear that I have provided receiving apparatus for a communication system incorporating signaling and indication means of relatively simple construction and that is free from operation due to surge voltages and from the telephone current. It is to be observed that the surge protector TH may be omitted and the delay period provided for relay R2 relied upon to avoid operation of the indication devices in response to surge voltages and to energy of the signaling frequency occurring in the telephone current.

Although I have herein shown and described only one form of receiving apparatus for communication systems embodying my invention, it is understood that various changes and modifications may be made therein within the scope of the appended claims without departing from the spirit and scope of my invention.

Having thus described my invention, what I claim is:

1. In receiving apparatus for a communication system using a carrier telephone current and a signaling current equivalent to the carrier modulated by a preselected voice frequency, the combination comprising, a demodulator arranged to receive such currents and operative to cause current of the voice frequencies to appear at its output terminals when the telephone current is received and to cause a current of said preselected frequency to appear at its output terminals when the signaling current is received, a direct current relay, circuit means including a filter tuned to pass only current of said preselected frequency and a rectifier to connect said relay to the demodulator output terminals for energization of the relay when said signaling current is received, indication means controlled by said relay and operable to a predetermined condition when the relay is energized, delay means includ-

ing a condenser associated with said indication means to avoid the establishing of said predetermined condition of the indication means for a given delay period when current is passed by said filter, and means including a contact of said relay to discharge said condenser to assure said given delay period when current is repeatedly passed by said filter.

2. In receiving apparatus for a communication system using a carrier telephone current and a signaling current equivalent to the carrier modulated by a preselected voice frequency, the combination comprising, a demodulator arranged to receive such currents and operative to cause current of the voice frequencies to appear at its output terminals when the telephone current is received and to cause a current of said preselected frequency to appear at its output terminals when the signaling current is received, a direct current relay, circuit means including a filter tuned to pass only current of said preselected frequency and a rectifier to connect said relay to the demodulator output terminals for energization of the relay when said signaling current is received, indication means controlled by said relay and operable to a predetermined condition when the relay is energized, means including a condenser controlled over contacts of said relay to prevent the establishing of said predetermined condition of the indication means for a given delay period when current is passed by said filter, and a discharge circuit including a contact of said relay to discharge said condenser to assure substantially the same said given delay period each successive time current is passed by said filter.

3. In receiving apparatus for a communication system using a carrier telephone current and a signaling current equivalent to the carrier modulated by a preselected voice frequency, the combination comprising, a demodulator arranged to receive such currents and operative to cause current of the voice frequencies to appear at its output terminals when the telephone current is received and to cause a current of said preselected frequency to appear at its output terminals when the signaling current is received, a direct current relay, circuit means including a filter tuned to pass only current of said preselected frequency and a rectifier to connect said relay to the demodulator output terminals for energization of the relay when said signaling current is received, another relay controlled over a front contact of the first mentioned relay, a loud speaker coupled to the output terminals of said demodulator over a back contact of said other relay, a condenser connected to said other relay over a front contact of the first mentioned relay to introduce a given delay in the picking up of said other relay and a discharge circuit including a back contact of the first mentioned relay for said condenser to assure such delay period when current is intermittently passed by said filter.

4. In receiving apparatus for a communication system using a carrier telephone current and a signaling current equivalent to the carrier modulated by a preselected voice frequency, the combination comprising, a demodulator arranged to receive such currents and operative to cause current of the voice frequencies to appear at its output terminals when the telephone current is received and to cause a current of said preselected frequency to appear at its output terminals when the signaling current is received, a direct current relay, a filter proportioned to pass only cur-

rent of said preselected frequency, a surge protector characterized by high initial resistance and a relatively low resistance after current is applied thereto for a period; circuit means including said filter and said surge protector to connect said relay to the output terminals of the demodulator to energize and pick up the relay when sustained signaling current is received but to block current from the relay when telephone current is received, and indication means controlled over a front contact of said relay.

5. In receiving apparatus for a communication system using a carrier telephone current and a signaling current equivalent to the carrier modulated by a preselected voice frequency, the combination comprising, a demodulator arranged to receive such currents and operative to cause current of the voice frequencies to appear at its output terminals when the telephone current is received and to cause a current of said preselected frequency to appear at its output terminals when the signaling current is received, a direct current relay, a filter proportioned to pass only current of said preselected frequency, a surge protector characterized by a high initial resistance and a relatively low resistance after a sustained flow of current; circuit means including said filter, said surge protector and a rectifier to connect said relay to the output terminals of the demodulator to energize and pick up said relay by a sustained 20 flow of the signaling current and to avoid picking up of the relay by energy of said preselected frequency occurring in the telephone current; a loud speaker, an indicator, and circuit means controlled by said relay to connect the loud speaker to the demodulator and deenergize the indicator when the relay is released and to disconnect the loud speaker and energize the indicator when the relay is picked up.

6. In receiving apparatus for a communication system using a carrier telephone current and a signaling current equivalent to the carrier modulated by a preselected voice frequency, the combination comprising, a demodulator arranged to receive such currents and operative to cause current of the voice frequencies to appear at its output terminals when the telephone current is received and to cause a current of said preselected frequency to appear at its output terminals when the signaling current is received, a direct current relay, a filter proportioned to pass only current of said preselected frequency, a surge protector characterized by a high initial resistance and a relatively low resistance after a brief delay when a sustained flow of current is effected; circuit means including said filter, said surge protector and a rectifier to connect said relay to the output terminals of said demodulator to energize and pick up said relay when sustained signaling current is received and to avoid energizing the relay by a surge voltage due to an extraneous magnetic field or said preselected frequency occurring in a telephone current; indication means controlled over a front contact of said relay, and a delay means including a condenser associated with said indication means to delay its response to the closing of said front contact.

7. In receiving apparatus for a communication system using a carrier telephone current and a signaling current equivalent to the carrier modulated by a preselected voice frequency, the combination comprising, a demodulator arranged to receive such currents and operative to cause current of the voice frequencies to appear at its output terminals when the telephone current is re-

ceived and to cause a current of said preselected frequency to appear at its output terminals when the signaling current is received, a direct current relay, circuit means including a filter tuned to pass only current of said preselected frequency and a rectifier to connect said relay to the demodulator output terminals for energization of the relay when said signaling current is received, another relay, a first condenser, a second condenser 10 permanently connected across the winding of said other relay, a resistor, a source of direct current, means including a back contact of said other relay and a front contact of the first mentioned relay to connect said first condenser across the winding of said other relay; an energizing circuit including said current source, a front contact of the first mentioned relay, said resistor and the winding of said other relay to pick up said other relay after a delay period predetermined by the time required to charge the first and second condenser in multiple through said resistor; said other relay released subsequent to the release of the first mentioned relay after a slow release period predetermined by the time required for the second condenser to discharge through the winding of said other relay, a first indicator controlled over a front contact of said other relay, and a second indicator controlled over a front contact of said other relay in series with a back contact of the first mentioned relay.

8. In receiving apparatus for a communication system using a carrier telephone current and a signaling current equivalent to the carrier modulated by a preselected voice frequency, the combination comprising, a demodulator arranged to receive such currents and operative to cause current of the voice frequencies to appear at its output terminals when the telephone current is received and to cause a current of said preselected frequency to appear at its output terminals when the signaling current is received, a direct current relay, circuit means including a filter tuned to pass only current of said preselected frequency and a rectifier to connect said relay to the demodulator output terminals for energization of the relay when said signaling current is received, another relay, a first condenser connected across the winding of said other relay over a back contact of said other relay and a front contact of the first mentioned relay, a second condenser permanently connected across the winding of said other relay, a first resistor, a direct current source; an energizing circuit including said current source, a front contact of the first mentioned relay, said resistor and the winding of said other relay to pick up said other relay with a slow pick-up period equal to the interval required to charge said condensers and to release said other relay with a slow release period equal to the interval required to discharge the second condenser through the winding of said other relay; a first indicator controlled over a front contact of said other relay, a second indicator controlled over a front contact of said other relay in series with a back contact of the first mentioned relay, and a loud speaker connected to the output terminals of the demodulator over a back contact of said other relay.

9. In receiving apparatus for a communication system using a carrier telephone current and a signaling current equivalent to the carrier modulated by a preselected voice frequency, the combination comprising, a demodulator arranged to receive such currents and operative to cause current of the voice frequencies to appear at its out-

put terminals when the telephone current is received and to cause a current of said preselected frequency to appear at its output terminals when the signaling current is received, a direct current relay, circuit means including a filter tuned to pass only current of said pre-selected frequency and a rectifier to connect said relay to the demodulator output terminals for energization of the relay when said signaling current is received, another relay, a first condenser connected across the winding of said other relay over a back contact of said other relay and a front contact of the first mentioned relay, a second condenser permanently connected across the winding of said other relay, a first resistor, a direct current source; an energizing circuit including said current source, a front contact of the first mentioned relay, said resistor and the winding of said other

relay to pick up said other relay with a slow pick-up period equal to the interval required to charge said condensers and to release said other relay with a slow release period equal to the interval required to discharge the second condenser through the winding of said other relay; a discharge circuit for said first condenser including a back contact of said other relay and a back contact of the first mentioned relay to maintain the slow pick-up period of said other relay substantially uniform when current is repeatedly passed by the filter, a first indicator controlled over a front contact of said other relay, and a second indicator controlled over a front contact of said other relay in series with a back contact of the first mentioned relay.

ANDREW J. SORENSEN.
